SEALING DEVICE

Charles A. Goddard, Cheshire, Conn., assignor to
Egbert Greeley Clark, Melrose, Mass.

Application July 1, 1933, Serial No. 678,703

4 Claims. (Cl. 292—307)

This invention relates to improvements in sealing devices such as are employed to prevent the opening or manipulation of devices which are intended to remain in locked position.

Seals for this purpose are commonly employed upon locking devices for freight cars, mail bags, and other types of closures, and are also employed in automatic fire extinguishing systems, such as sprinkler systems which are provided with normally open valves adapted to be closed temporarily to permit the setting or replacement of fusible devices forming part of the sprinkler head, and which when sufficiently heated will be released to open the sprinkler heads and thereby discharge extinguishing fluid upon the fire. After such fusible devices have been installed or replaced, the valves in the pipes are opened to permit the fire extinguishing fluid to pass to the sprinkler heads and to insure that such valves remain properly in open position inspectors are required to lock the valves in open position, usually by a keeper passed through registering apertures in portions of the valve, and then to seal the keeper to prevent its removal and the closing of the valve.

The principal object of the present invention is to provide a seal of the character described of small and economical construction and which when locked upon the keeper cannot be removed.

More particularly the present invention comprises certain improvements upon the sealing device disclosed in Patent No. 1,911,060, granted May 22, 1933, to Egbert Greeley Clark.

A preferred embodiment of the invention is illustrated in the accompanying drawing, in which,

Fig. 1 is a vertical diametrical sectional view showing the clamping device of the seal in locking engagement with the keeper, the cap being omitted;

Fig. 2 is a similar view showing the clamping member in locking engagement with the keeper and the preferred means for locking the cap within the chamber of the body; and,

Fig. 3 is a plan view of the seal shown in Fig. 1, with the cap removed, illustrating a preferred form of resilient locking device for preventing the removal of the cap.

The preferred form of seal illustrated in the drawing comprises a preferably cylindrical body 1 of metal having a channel extending downwardly from one face thereof providing a chamber 2 having a cylindrical peripheral wall 3. An integral stud 4 extends upwardly from the central portion of the body concentric with the periph-

eral wall 3 and is provided with a vertical bore 5 which intersects a transverse recess 6 which preferably extends diametrically through the body beneath the stud 4. The vertical bore desirably crosses the recess 6 and provides a depression 7 in the lower wall of the recess 6.

A suitable member is inserted in the bore and forced downwardly into clamping engagement with the keeper which, in the preferred construction illustrated herein, is in the form of a looped wire 8 which is passed through the device to be locked and the legs 9 and 10 of the looped wire passed through the recess 6. The locking device desirably is forced downwardly sufficiently to bend the portions of the wire engaged by the locking member into the recess 7, thereby providing a bight which will effectively prevent withdrawal of the legs of the loop.

Any suitable locking device may be employed. In the particular construction illustrated the walls of the vertical bore 5 are screw threaded and a locking screw 11 mounted therein which is provided with a pair of substantially radial vertical shoulders 12, only one of which is shown, having inclined surfaces upon the opposite sides of and approaching the shoulders. The shoulders are offset sufficiently from radii to permit the bit of the screw driver, or other propelling tool, positively to engage the shoulders when the tool is rotated in a direction to advance the screw, while the inclined surfaces prevent effective engagement of the screw driver with the screw when the propelling tool is rotated in the opposite direction. Desirably the screw is so short that when it is in locking engagement with the legs of the keeper its upper end or head will be located so far within the bore that a punch, nail, or other device cannot be inserted to engage the screw at such angle as will permit rotation of the screw by pressure, or by impact upon the punch, nail, or other device.

The construction above described may be and desirably is similar to that disclosed in the patent to Clark aforesaid.

The present device, however, comprises novel means for preventing access to the clamping member or screw which engages the keeper. The means for preventing the access to the clamping means comprises a cap 13 having a peripheral flange 14, preferably of such width to engage the bottom wall 15 of the chamber when the cap is applied to the chamber of the body, so that the plane of the top of the cap will lie substantially flush with the upper edge of the peripheral wall 3 of the body. The flange may

be provided with a beveled lower edge 16 for a purpose which will hereinafter be described.

The means for locking the cap in assembled position illustrated in Fig. 2 comprises means within the chamber of the body adapted when the cap is in assembled position to engage the stud and the flange in such manner as to prevent removal of the cap when the flange thereof is once inserted in the chamber.

10 The preferred means illustrated in the accompanying drawing comprises a thin resilient sheet metal plate which is fixedly secured to the stud 4 and provided with means to engage positively the inner face of the flange 14 at a distance from its edge. In the particular construction illustrated a substantially rectangular plate 17 is mounted upon the shouldered upper portion of the stud and a portion of the stud extending therebeyond is expanded or riveted over 20 to provide a locking flange 18 which permanently secures the plate upon the stud. The edges 19 of the plate desirably are slightly concaved to provide sharp points 20 which when the plate is in assembled position, illustrated in Fig. 1, lie 25 in such proximity to the inner face of the peripheral wall 3 of the body that when the flange of the cap 13 is forced into the body the engagement with the points will cause the plate to be bent slightly downwardly, as illustrated in Fig. 2, thus causing the points to engage the inner 30 face of the flange at such angle that the removal of the cap will be impossible as any force tending to raise the cap will tend to straighten the plate and increase the effective diameter of the plate connecting the points which engage the cap.

It has heretofore been stated that the lower portion of the cap may if desired be slightly beveled inwardly and the purpose of such bevel 40 is to facilitate the entry of the flange of the cap when the cap is applied to the body.

It will be obvious that by reason of the present construction a greatly simplified sealing device is provided which can be economically constructed and which will be most effective in 45 operation.

It will be understood that the particular embodiment of the invention shown and described herein is of an illustrative character and is not 50 restrictive of the meaning and scope of the following claims.

Having thus described the invention, what is claimed as new, and desired to be secured by Letters Patent, is:

55 1. A seal comprising an integral chambered body having a cylindrical peripheral wall, an integral stud extending into the chamber of said body and provided with a transverse recess beneath said stud to receive the device to be sealed,

a locking member mounted in said stud movable in a direction to lock said device in said recess, a cap having a flange peripherally fitting within the wall of said chamber and fully enclosed thereby, and a resilient plate mounted on said stud having angular projections engaged by said flange when the cap is in assembled position for effecting a locking engagement between said cap and said stud.

2. A seal comprising an integral chambered body having a cylindrical peripheral wall, an integral stud extending into the chamber of said body and provided with a transverse recess beneath said stud to receive the device to be sealed, a locking plate mounted on said stud movable in a direction to lock said device in said recess, a cap having a peripheral flange fitting within the wall of said chamber, and resilient locking plate within said chamber mounted on said stud having pointed portions engaging said flange when the flange of the cap is inserted in said chamber and acting to prevent removal of said cap.

3. A seal comprising an integral chambered body having a cylindrical peripheral wall with an integral stud extending centrally into said chamber and provided with a transverse recess beneath said stud to receive the device to be locked, a locking member mounted axially in said stud and movable only in a direction to lock the device in said recess, a cap having a peripheral flange fitting within the wall of said recess, and a resilient metallic locking member rigidly mounted on said stud having means extending into proximity to said wall for positively engaging said flange when inserted in said chamber and acting to prevent removal of said cap, the lower edge of said flange being beveled inwardly to facilitate the insertion of the cap into said chamber.

4. A seal comprising an integral chambered body having a cylindrical peripheral wall with an integral stud extending centrally into said chamber and provided with a transverse recess beneath said stud to receive the device to be locked, a locking member mounted axially in said stud and movable only in a direction to lock the device in said recess, a cap having a peripheral flange fitting within the wall of said recess and fully enclosed by said wall, and a thin stiff resilient metal locking plate of angular form fixedly mounted on said stud having pointed corner members extending into proximity to the wall of the chamber and adapted to be bent slightly downwardly by the flange of said cap when the latter is applied to said body and thereupon to engage the flange and prevent the removal of the cap.

CHARLES A. GODDARD.
